UNITED STATES PATENT OFFICE.

LEWIS E. WATERMAN, OF MOLINE, ILLINOIS, ASSIGNOR TO THE EMERSON MANUFACTURING COMPANY, OF ROCKFORD, ILLINOIS.

CORN-PLANTER.

SPECIFICATION forming part of Letters Patent No. 657,474, dated September 4, 1900.

Application filed January 16, 1900. Serial No. 1,701. (No model.)

To all whom it may concern:

Be it known that I, LEWIS E. WATERMAN, a citizen of the United States, residing at Moline, in the county of Rock Island and State 5 of Illinois, have invented certain new and useful Improvements in Corn-Planters, of which the following is a specification.

This invention relates to the details of construction in a corn-planter, hereinafter set 10 forth.

In the accompanying drawings, Figure 1 is a plan view of my improved corn-planter. Fig. 2 is a vertical section through the wire-reel. Fig. 3 is a horizontal section through the runner, showing the wheel for operating the valve in the heel of the runner. Fig. 4 is a 15 longitudinal section of the corn-planter. Fig. 5 is a vertical section of the connection between the main axle and the runner-frame. Fig. 6 is a vertical section of one of the runners. Fig. 7 is a view of the link connecting the hand and foot levers. Fig. 8 is a plan view of the checking device. Fig. 9 is a similar view in which the grooved roller is turned 20 to throw off the wire. Fig. 10 is a side elevation of the checking device. Fig. 11 is a front elevation of the device, and Fig. 12 is a view of the pivoted fork.

The main or wheel frame consists of the 25 axle 1, supporting side bars 2 and end bar 3. A brace-bar 4 connects the side bars. Wheels 5 support the axle. The runner-frame consists of the bars 6 and 7, supporting runners or furrow-opener 8, and a shaft 9 for actuating the seed-dropping mechanism. The side bars 2 of the main frame are pivotally connected with the bar 6 of the runner-frame. A tongue 10 is connected to the runner-frame. A seat-support 11 has a connection with the 30 brace-bar 4 and supports a toothed quadrant 12. A hand-lever 13 has a pivotal connection with the seat-support, having a rear extension 14, to which is pivoted a foot-lever 15, and a forward extension 16 has a link 17, connecting it with a bracket 18, extending 35 from the rear end of the tongue. A coiled spring 19 surrounds the link 17, thereby forming a flexible connection between the main and runner frames. A thumb-lever 20 has a 40 pivotal connection with the hand-lever, and a rod having its upper portion 21 pivotally con-

nected with the thumb-lever has a horizontal extension 22 for engagement with the teeth of the quadrant 12 and passes through an opening 23 in the hand-lever 13, and a downward portion 24 connects with the foot-lever. This rod acts as a dog and can be raised free of the toothed quadrant either by the thumb-lever or foot-lever, and the hand-lever can be moved by means of the hands or feet. A 45 pressure down on the foot-lever will move the horizontal portion 22 of the rod in contact with the hand-lever and form a rigid connection between the foot and hand levers. A connection is formed between the axle 1 and 50 shaft 9 operating the seed-dropping mechanism in order that the planter can be operated as a drill. A toothed wheel 25 is secured to the axle and is inclosed in a casing 26, having a forward extension 27, to which is pivoted 55 a bar 28, having its rear end 29 in fork form. A toothed wheel 30 is located within the casing and supported upon a shaft 31, extending through side opening in the casing, the shaft supported by the ends of the fork. A sprocket-wheel 32 is secured to the shaft 31. A series of 60 sprocket-wheels 33 are secured to the shaft 9, and a chain 34 connects the sprocket-wheels. The bar 28 has a reduced end 35 located in an opening in the bar 7 of the runner-frame. 65 When the runner-frame is in working position, the parts will appear as shown in solid lines at Fig. 5, in which the toothed wheels 25 and 30 are in engagement, and the rotary movement of the axle will impart a rotary 70 movement to the shaft 31 of the runner-frame through the chain connection. When the runner-frame is raised, the parts will appear as shown in dotted lines, Fig. 5, in which the toothed wheels 25 and 30 are separated, and 75 the toothed wheel 25 can rotate without imparting movement to the chain. This connection is used when it is desired to drill corn, and when the planter is used as a check-rower 80 the chain is removed.

To the axle 1 is secured a sprocket-wheel 95 36, over which a chain 37 is placed.

A wire-reel is supported by the main frame in the following manner: Two brackets 38 and 39 are supported by the side bars of the 100 main frame, each having a tubular horizontal portion. The reel proper is composed of

two heads 40, their center portions being convex and provided with square openings. The center section 41 of the reel is in drum form, having lips 42 passing through openings in the head-sections and clenched, thereby forming a light and strong reel. The tubular portion of the bracket 38 supports a shaft 43, having a square end and a collar. The tubular portion of the bracket 39 supports a shaft 44, having one end square and of a size to enter the square opening in the head of the reel. The other end of the shaft has a square section 45 and a round section 46 screw-threaded. A cone friction-gear 47 is located on the square section 45 of the shaft. A sprocket-wheel 48, having a cone extension 49, is located on this section of the shaft; also a cone friction-gear 50 engaging the extension of the sprocket-wheel. A spring 51 is located between the cone friction-gear 50 and nut 52, and by means of the nut the friction-contact between the parts can be regulated. As the sprocket-wheel 48 has an internal and an external friction-gear and the friction-gears regulated by a spring, the reel is driven with any required amount of power and will slip when from any cause the reel is held stationary while the sprocket-wheel is running. The drum can be disengaged from its connection with the shafts 43 and 44 by withdrawing the pin 53 and moving the shaft 43 sufficiently to allow the drum to become disengaged from the shaft 44.

In Figs. 3 and 6 are shown views of one of the runners which are secured to the bars 6 and 7 of the runner-frame. A cavity 54 is formed in the rear portion of the runner 8, within which is located a valve 55, having a pivotal connection at its center 56 with the runner, its lower portion having the rear wall 57 and a front wall 58 extending upwardly and forwardly. The lower end of the valve are located over an offset 59 in the heel of the runner. An opening 60 is formed in the upper face of the runner, through which the corn is dropped into the valve. Upon the shaft 9 is located a toothed pinion 61 and a star-wheel 62, connected by a sleeve 63, the star-wheel located in a recess 64 in the upper face of the runner and held in position by a clamp 65. The pinion is designed to engage with a toothed wheel connected with the seed-plates, located in the seed-box, and by which an intermittent rotary movement may be imparted to the plates. The star-wheel engages the upper end of the valve 55 and moves it on its pivotal connection with the runner and moves its lower end free of the ledge 59, so the corn will drop into the valve and fall onto the ledge when the parts are in the position shown at Fig. 6, and will be thrown free of the ledge when the valve is moved rearward by the star-wheel. A flat spring 66, secured to the valve, holds it in the position shown in the drawings, but permits it to be moved by the star-wheel. Means for imparting an intermittent rotary movement to the shaft 9 and to the

seed-plate and valves are located at each side of the runner-frame, supported by the bars 6 and 7 of the runner-frame, and consist of a plate 67, secured to the bars 6 and 7. The rear end of this plate supports a roller 68 and a guide 69, the roller being vertically adjustable. An eye 70 is supported by the bar 7 of the runner-frame. A ratchet-wheel 71 has a connection with the rotating bar 9. A yoke 72 is pivoted upon the hubs of the ratchet-wheel and is in two parts, joined together by the rivets 73. A dog 74 has a pivotal connection with one of the rivets, its rear end adapted to engage the teeth of the ratchet-wheel. A fork 75 has a pivotal connection with the yoke 72 in a manner to allow it to swing side-wise, as shown in dotted lines, Fig. 12. From the end plate 67 extends an arm 76, to which is hinged a support 77. To this support is pivoted a plate 78, having a slot 79 in one end and its other end having an extension or hook 80. A roller 81 is mounted on the support 77, and above this roller is pivoted a plate 82, having an opening 83. The plates 78 and 82 are connected by a bushing 84, which is adjustable in the slot 79 of the plate 78 by means of the clamping-nut 85. The extension or hook 80 of the plate 78 passes under the hook 86, rising from the end bar 67. An arm composed of the branches 87 and 88 has a pivotal connection with an ear 89, rising from the end bar 67. The branch 88 has a spring 90 connecting it with the dog 74, and the branch 87 bears against the extension 80 and holds it in engagement with the hook 86. From the end bar 67 extend two arms 91, forming a guide. The check-wire is placed in the guide 91 and in the grooved roller 81, in the forked arm 75 over the roller 68, and under the guide 69, and as the planter is drawn over the ground the forked arm 75 will be moved rearward, and as the dog is in engagement with the ratchet-wheel 71 the wheel and shaft 9, connected therewith, will be intermittently rotated, the spring 90 acting to hold the dog in engagement with the ratchet-wheel and to return the forked arm after the button has passed it. A stop 92 limits the forward movement of the forked arm and a stop 93 limits its backward movement. A cord 94 (shown in Fig. 1) is connected with the plate 82, passing through the eye 70 and through an opening 95 in the end bar and extends within reach of the driver. By pulling on this cord the plates 78 and 82 will be moved on their pivotal connection with the support 77, which will move the extension 80 of the hook 86 against the spring 125 action of the branch 87 of the pivoted arm, when the roller 81 will fall over into the position shown at Fig. 9, thereby liberating the check-wire from its engagement with the forked arm, roller 81, and guide 91. The forked arm 75 will turn outward and allow the wire to slip out. Should the checking-wire draw sidewise, it would come in contact with the bushing 84 and move the plates in

the same manner as is done by the cord. By means of the slot 79 the bushing can be adjusted so that the device will be tripped at any desired angle of the wire.

5 I claim as my invention—

1. In a corn-planter, the combination of a main frame and runner-frame, a rotating toothed wheel, a pivoted casing, an arm having a connection with the runner-frame and a pivotal connection with the casing, and a toothed wheel supported by the arm adapted to be moved into and out of engagement with the rotating toothed wheel by the movement of the runner-frame.
- 15 2. In a corn-planter, the combination of a main frame and runner-frame, a rotating toothed wheel, a pivoted casing, an arm having a connection with the runner-frame and a pivotal connection with the casing, a toothed wheel supported by the arm adapted to be moved into and out of engagement with the rotating toothed wheel by the movement of the runner-frame and a connection between the toothed wheel and rod of the runner-frame
- 25 for operating the seed-dropping devices.
3. In a corn-planter, the combination of a main frame and runner-frame having a hinged connection, a hand-lever and toothed quadrant, the hand-lever having an extension, a foot-lever pivoted to the extension, a thumb-lever on the hand-lever, and a rod connecting the thumb and foot levers and having a horizontal portion for engaging the toothed quadrant.
- 35 4. In a corn-planter, the combination of a main frame, a sectional shaft supported by the main frame and a wire-reel located between the sections of the shaft and removably supported thereby.
- 40 5. In a corn-planter, a main frame, a bearing supported by the main frame, a shaft supported by the bearing, a wire-reel supported by the shaft, the shaft having a squared section and a round screw-threaded end, two cone friction-gears supported upon the square portion of the shaft one being external and the other internal, a nut on the screw-threaded end of the shaft, a spring between the nut and the internal cone friction-gear and
- 45

sprocket-wheel provided with internal and 50 external cone friction-gear engaging the cone friction-gear supported by the shaft, the other end of the reel being suitably supported by the main frame.

6. In a corn-planter, a runner having a recess in its upper face, a combined star-wheel and beveled pinion, the star-wheel located in the recess, and a valve operated by the star-wheel.

7. In a corn-planter, a runner-frame supporting an end bar, a shaft supported by the frame, a ratchet-wheel secured to the shaft, a forked lever, a dog engaging the ratchet-wheel, a forked lever having a bodily movement in the lengthwise direction of the checking-wire and a pivotal movement transverse thereto, a guide-wheel for the checking-wire having a pivotal connection with the end bar, a catch holding the wheel in a horizontal position and a spring holding the catch. 70

8. In a corn-planter, a runner-frame supporting an end bar, a shaft supported by the frame, a ratchet-wheel secured to the shaft, a yoke pivotally supported by the shaft, a dog supported by the yoke, a forked lever 75 pivotally supported by the yoke, a guide-wheel for the checking-wire having a pivotal connection with the end bar, a catch holding the wheel in a horizontal position a pivoted bar holding the catch and a spring connecting the bar and dog.

9. In a corn-planter, a runner-frame supporting an end bar, a guide-wheel for the checking-wire having a pivotal connection with the end bar, a catch holding the wheel 85 in a horizontal position, and an adjustable bushing against which the checking-wire may press to release the wheel.

10. In a corn-planter, the combination of a main frame, a sectional shaft supported by 90 the main frame, one section made longitudinally movable and a wire-reel located between the sections of the shaft and removably supported thereby.

LEWIS E. WATERMAN.
